UNITED STATES PATENT OFFICE.

FRANCIS J. McCARTY, OF SAN FRANCISCO, CALIFORNIA; HENRY A. McCARTY, ADMINISTRATOR OF SAID FRANCIS J. McCARTY, DECEASED, ASSIGNOR TO McCARTY WIRELESS TELEPHONE CO., OF SAN FRANCISCO, CALIFORNIA, A CORPORATION OF CALIFORNIA.

WIRELESS TELEPHONE.

No. 889,031.

Specification of Letters Patent.

Patented May 26, 1908.

Application filed December 12, 1904. Serial No. 236,495.

To all whom it may concern:

Be it known that I, FRANCIS J. McCARTY, citizen of the United States, residing at the city and county of San Francisco and State 5 of California, have invented new and useful Improvements in Wireless Telephones, of which the following is a specification.

This invention relates to improvements in wireless telephone systems and apparatus 10 therefor by means of which telephonic messages may be transmitted without the aid of wires or other mechanical intermediate connections between the stations.

The invention consists in a combination of 15 devices whereby vibrations produced by vocal sounds in the apparatus are capable of transmission through the medium surrounding the earth without the aid of wires or similar connections.

20 The invention is hereafter described with reference to the accompanying drawings, in which—the Figure is a diagrammatic view of the transmitting apparatus.

A is a mouth-piece with the usual or any 25 suitable diaphragm extended within it and 2 is a tube into the side of which the mouth piece opens. At one end of this tube is the microphone transmitter as at 3, and at the opposite end of the tube is another trans- 30 mitter diaphragm 4.

5 represents an induction coil having two primary windings of wires 6 and 7, and in conjunction with these an insulated secondary winding as at 8. The first primary wire 35 6 is connected through a branch of the wire 6^a, and a binding post 9, with the contact screw or point 10, which is adjustable in the non-conducting case within which the dia- 40 phragm 4 is fixed, and this diaphragm has the contact 11 corresponding with the contact 10. The contacts may be of platinum. From the binding-post 9, the wire 6^a passes into the coil 5, thence passing out of it, through wire 6 connects with the battery 12, 45 and thence to the binding post 13 of the transmitter 4.

14 is a condenser interposed between the binding-post 9 and the primary wire 6, and it serves to prevent sparking at the contacts 50 of the transmitter.

The microphone transmitter 3 has the binding-posts 15 and 16 with which the ends

of the second primary wire are connected with a resistance interposed as at 17.

In the operation of the device, words 55 spoken into the mouth piece A will cause a vibration of both the diaphragm 4 and that within the transmitter 3, and the vibration of the microphone transmitter being synchronous with the vibrations of the dia- 60 phragm 4, the effect produced by the double primary winding of the coil 5 is transmitted through the secondary winding 8 and the discharge points 18 to the aerial conductor in the line shown by the arrow 19 and thence 65 to any suitable receiver.

I have ascertained that any primary of an induction coil which has a second layer of wire wound over it serves to choke off the effect of current in the first primary upon the 70 secondary, if it be suddenly short-circuited and that by connecting an ordinary microphone transmitter across the ends of this second primary, it will vary the effects of the first primary upon the secondary when the 75 mouth piece is spoken into, without the aid of a battery when used over short distances, but to obtain this effect over long distances I usually employ a few battery elements.

Having thus described my invention, what 80 I claim and desire to secure by Letters Patent is—

1. In a wireless telephone, means for intensifying the vibrations from a transmitting device, said means consisting of a transmitting diaphragm with metallic contact points, an opposed microphone transmitter, an induction coil including two primary, and a secondary winding, one of said primary, windings being connected with the dia- 90 phragm, and the other with the microphone, a local battery, connections there-through with the coil, a spark-gap interposed in the secondary circuit, and aerial and ground wires connected with said secondary wire. 95

2. In a telephone, means introduced into the transmission device, said means including a mouth-piece, a transmitting diaphragm with metallic contacts, and an opposed mi- 100 croscope transmitter, two primary windings connected with the diaphragm and microphone coil respectively, a secondary coil energized thereby, a spark-gap device connected with the secondary coil, through

which the surrounding aerial medium is affected to transmit articulate speech between a sending and a receiving medium.

3. In a telephone, means introduced into the primary circuit, said means comprising a plurality of primary windings, a secondary coil which is energized thereby, a mouth-piece, a transmitting diaphragm with metallic contacts and a microphone transmitter actuated in unison, means whereby a spark is produced, and the aerial transmitting medium is affected to transmit articulate speech, and a mechanism capable of receiving transmitted speech.

4. In a telephone, means introduced into the primary circuit, said means comprising a plurality of primary windings whereby a secondary coil is energized, a mouth piece, a transmitting diaphragm with metallic contacts and a microphone transmitter actuated in unison means whereby a spark is produced, and the aerial transmitting medium is affected to transmit articulate speech, and a receiving mechanism capable of receiving transmitted speech.

5. In a wireless telephone, means for intensifying the vibrations between a primary telephone transmitter and the aerial transmission device, said means comprising a chamber with which the mouth-piece is connected, a microphone transmitter and a transmitting diaphragm connected therewith, an induction coil with double primary windings connected respectively with the transmitters, and a secondary circuit energized thereby connected with the aerial wire, and having a spark gap, and a battery, a resistance, and a condenser in the primary circuits.

6. In a wireless telephone, a mouthpiece, a transmitting diaphragm, a battery, an induction coil with two primary windings, wires connecting one of said windings and the diaphragm, a microphone transmitter, connections between said transmitter and the other primary winding, and a secondary coil with a spark-gap and aerial and ground connections.

7. In a wireless telephone, a mouth-piece, a transmitting diaphragm with metallic contacts, an induction coil and battery and connections with the transmitter, a microphone transmitter actuated in unison with the first named transmitter, a second primary winding of the induction coil connected with the

microphone transmitter, and a resistance interposed between said transmitter and the connected primary winding of the coil.

8. In a wireless telephone, a mouth-piece, a transmitting diaphragm, a battery, an induction coil, wires connecting the coil and transmitter, a microphone transmitter, means whereby it is actuated in unison with the first named transmitter, a second primary winding of the induction coil, said second winding being connected with the microphone transmitter, and a condenser interposed between the local battery and the first transmitter.

9. In an apparatus of the character described, a chamber, a microphone transmitter, a transmitting diaphragm at opposite sides, a mouth-piece connecting with the intermediate portion of the chamber, a coil composed of primary windings, one of which is connected with the microphone transmitter and the other with the diaphragm, coacting contacts one of which is carried by the diaphragm, and a secondary coil with spark gap and aerial connections.

10. In an apparatus of the character described, a chamber or case with microphone transmitter, a transmitting diaphragm and mouth-piece, a coil composed of double primary windings, and a secondary winding with spark gap and aerial connections, said primaries being connected respectively with the microphone and with the transmitter diaphragm, co-acting contacts one of which is carried by the diaphragm, and a battery and resistance within the primary circuit.

11. In an apparatus of the character described, a microphone transmitter, a mouth-piece, and a transmitting diaphragm, a contact point carried by the diaphragm, a fixed contact with which the diaphragm contact co-acts, a coil consisting of double primary windings, one of which connects with the fixed contact, and the other with the microphone transmitter, a secondary coil with spark gap and aerial wires, and a battery resistance and condenser in the primary circuits.

In testimony whereof I have hereunto set my hand in presence of two subscribing witnesses.

FRANCIS J. McCARTY.
